UNITED STATES PATENT OFFICE.

FREDERICK C. STIMMEL, OF CHATTANOOGA, TENNESSEE, ASSIGNOR TO THE CASEY-HEDGES COMPANY, OF CINCINNATI, OHIO, A CORPORATION OF OHIO.

DESIGN FOR A STANDARD FOR LIGHTS.

41,439.

Specification for Design.

Patented June 6, 1911.

Application filed April 3, 1911. Serial No. 618,773. Term of patent 7 years.

To all whom it may concern:

Be it known that I, FREDERICK C. STIMMEL, a citizen of the United States, residing at Chattanooga, in the county of Hamilton and State of Tennessee, have invented a new, original, and ornamental Design for Standards for Lights, of which the following is a specification, reference being had to the accompanying drawing, forming part thereof.

The figure is a perspective view of the standard for lights, showing my design.

I claim:

The ornamental design for a standard for lights, as shown.

FREDERICK C. STIMMEL.
